UNITED STATES PATENT OFFICE.

HOWARD K. KING, OF PHILADELPHIA, PENNSYLVANIA, ASSIGNOR TO CHAMBERS BROTHERS COMPANY, A CORPORATION OF PENNSYLVANIA.

CUT-OFF MECHANISM FOR BRICK-MACHINES.

1,077,226.

Specification of Letters Patent.

Patented Oct. 28, 1913.

Application filed March 7, 1908. Serial No. 419,764.

To all whom it may concern:

Be it known that I, HOWARD K. KING, a citizen of the United States, residing at Philadelphia, in the county of Philadelphia, 5 State of Pennsylvania, have invented a new and useful Cut-Off Mechanism for Brick-Machines, of which the following is a specification.

My invention relates to wire cut-off mechanism for brick machines and the like.

The object of my invention is to provide improved means for supporting and moving a cut-off wire through the bar during the travel of the bar and in a plane at the required angle to said direction of travel.

My invention comprises improved means for movably supporting the wire supporting and actuating mechanism so that the same shall have a reciprocating movement, 20 said movement in one direction being with the movement of the bar.

My invention comprises automatic means for controlling said movement by the variation in speed of travel of the bar.

25 My invention comprises automatic means whereby the efficiency of the helping power communicated to the moving clay bar shall be affected by the variation in the force exerted by the clay bar itself.

30 Referring to the drawings:—Figure 1 is a side elevation of my device. Fig. 2 is a vertical cross-section on line 2—2 of Fig. 1 on an enlarged scale. Fig. 3 is a plan view of the main part of my mechanism on the 35 same scale as that of Fig. 2. Fig. 4 is a vertical section on line 4—4 of Fig. 3. Fig. 5 is a detail of the cam wheel and arm on a slightly larger scale than shown in Fig. 1. Fig. 6 is a fragmentary view in section 40 showing the wire wheel and part of a supporting roller in section, and a wire supporting hook carried on the wire wheel. Fig. 7 is a view of the wire wheel and the spring supported wire hook. Fig. 8 is a section on line 8—8 of Fig. 7. Fig. 9 is a section on line 9—9 of Fig. 7. Fig. 10 is a section on line 10—10 of Fig. 7. Fig. 11 is a view showing a portion of the wire ring, a supporting roll in section and a portion of 45 the rocking frame for supporting said roll. Fig. 12 is a plan view showing a side slit 50

and wire cleaning mechanism. Fig. 13 is a side elevation of same. Fig. 14 is a detail of the plectrum shown in Fig. 12. Fig. 15 is a section on line 15—15 of Fig. 13. Fig. 16 is a longitudinal vertical section of the driving shaft and clutch mechanism. Fig. 17 is a plan view of the receiving end portion of the regulating belt and associated mechanism being a continuance of the plan view shown in Fig. 3. Fig. 18 is a cross-section on line 18—18 of Fig. 17. Fig. 19 is a vertical section on line 19—19 of Fig. 1. Fig. 20 is a vertical section on line 20—20 of Fig. 19. Fig. 21 is a vertical section on line 21—21 of Fig. 19. Fig. 22 is a perspective view of a bushing. Fig. 23, Sheet 2, is a fragmentary elevation showing the shaft 27 connecting the regulating pulley with gear 28. Fig. 24 is a sectional detail of ball-bearing measuring pulley 26. Fig. 25 is a sectional detail of ball-bearing of the end pulley 91.

This invention relates to an improved cut-off for brick machines. It is applicable to 75 brick machines in many respects similar to that shown in patent to King and Chambers No. 678,259; July 9, 1901.

The bar of clay is delivered to the regulating belt 25 in the usual way. The shaft 27 80 of the regulating pulley is operatively connected with gear 28 through two universal joints 29, one being shown in Figs. 2 and 3, and both being shown in Fig. 23. These universal joints are introduced to permit a 85 translative movement of shaft 27 with respect to the shaft portion of gear 28, which rotates in a fixed bearing, for the purpose hereinafter explained. The gear 28 co-operates with pinion 30 on shaft 31 provided 90 with the beveled gear 32, which co-operates with beveled gear 33 on shaft 34, see Figs. 2 and 3. Shaft 34 also carries gear 35, which is connected, through the train of gears 36 and 37, with the gear on one friction element 38; the other co-operating friction element is 39, see Fig. 16, Sheet 7. The element 39 is feathered on the shaft 40 which is the main driving shaft connected with the source of power. By means of proper adjustment between the two friction elements 95 suitable helping power is communicated 100

through the gears enumerated, to the regulating pulley 26, to coöperate with the force exerted by the moving bar of clay. Upon the shaft 34 is also provided the gear 41, 5 which coöperates with teeth on the wire ring 42, see Fig. 3, which carries the cutting wire 43. On shaft 31 is carried the cam wheel 44, which coöperates with the roller 45, see Figs. 1 and 5, for the purpose herein- 10 after explained.

Regulating frame.—The regulating frame 46 supporting the regulating belt 25 and pulley 26, is mounted on four ball bearings 47, such as are shown in detail in Figs. 18, 15 19 and 20, at approximately its four corners. This permits a slight longitudinal movement of said regulating frame, controlled by the fluctuations in the movement of the clay bar. The movement of the frame 46 20 is communicated, through bracket 48, see Figs. 1 and 16, to lug 49 on lever 50 pivoted at 51 and secured at 52 to a thrust box 53 in which rotates the collar 54 secured to shaft 40 by the pin 104. In this way the movement of the frame 46 affects, through the shaft 40, the efficiency of engagement between the friction elements 38 and 39. It is to be understood that the shaft 40 and element 39 always run at higher speed than 25 element 38, and that therefore there is always a slip between elements 38 and 39. The tendency of the acceleration of the movement of the clay bar is to push the regulating frame forward, which, in the 30 manner above explained, serves to increase the efficiency of engagement between the friction elements, and consequently the helping effect of the driving shaft 40 upon the regulating pulley 26.

Arbitrary control.—The arbitrary control of the adjustment between the friction elements is secured by the hand lever 87, see Figs. 17 and 18, secured to the lever 50 which carries the lug 49 and operates automatically as above described. One of the purposes of the hand lever is for transferring power to the regulating pulley at the beginning of the operation of the machine, before the clay-bar exerts its power.

Preliminary adjustment.—The preliminary adjustment between the friction elements is secured by the following mechanism: The threaded sleeve 99 is secured to the shaft 40 by the pin 100. The collar 101 55 has a threaded end for coöperating with the threaded sleeve 99 and is adapted to abut at its other end against the friction element 39. By turning collar 101 in one direction or the other, relatively to sleeve 99, the proper normal adjustment of element 39 is 60 secured. The holes 102 are provided for engaging the wrench or spanner used for turning said member 101. The lock nut 103 is provided for maintaining members 99 and

101 in said position of adjustment. This 65 method of adjustment is provided for the original assembling and also for taking up the wear between the friction elements. A further preliminary adjustment, with respect to the tension exerted by the regulating frame on friction elements 38 and 39, is 70 secured by the hand wheel 55, see Fig. 3, threaded on the rod 56 which is secured at the stationary point 57, so that the hand wheel 55 will engage the bracket 58 which 75 is secured to the regulating frame 46. It is to be understood that this adjustment is a very fine one, so that the slightest fluctuations of the rate of travel of the clay bar will affect the tension between the friction 80 elements, so that the efficiency of the helping power communicated to the moving clay bar shall be affected by the variation in the force exerted by the clay bar itself.

Anti-friction bearing of friction elements.—Since it is desirable to secure the full advantage of a nice adjustment between the friction elements 38 and 39, it is 85 important that this result shall not be counteracted by other frictional conditions. For example, when member 39 is forced into tighter relation with member 38, which members always have a slipping engagement with each other, the tendency is to cause the transference of greater power 90 from 39 to 38. By forcing 39 against 38 however, 38 will naturally be forced with greater efficiency against its thrust bearing, and, if special provision was not provided, a resultant greater friction would be caused 95 between said member 38 and its thrust bearing, which would in a large measure, overcome or counterbalance the result of the delicacy of adjustment between said members 38 and 39. I therefore provide the ball- 100 bearings 116, see Fig. 16, so as to reduce to a minimum the friction between said member 38 and its thrust bearing. Since the regulating belt, regulating pulley and regulating frame also enter into the automatic 110 control of the said friction elements, it is desirable for the same reason to eliminate disturbing frictional conditions with respect to these instrumentalities. The regulating belt is under considerable tension and 115 is required to sustain the great weight of the long bar of clay. I therefore provide ball-bearings for the regulating pulley 26 as shown in Fig. 24, and ball bearings for the roller 91 at the other end of the regulating belt as shown in Fig. 25. I mount the intermediate supporting rollers 89 in arguto or improved wooden bushings which greatly 120 reduce friction without lubrication. As has already been stated, the regulating frame is 125 mounted on ball bearings at its four corners.

Wire wheel.—The wire wheel 42 has a peripheral engagement with the rollers 59,

60 and 61, by which it is supported, see Figs. 2, 4 and 6, and as already explained, is driven by the gear 41. The wire wheel carries the wire 43, extending diametrically 5 across it, secured at one end to the fixed stud or hook 62 and at the other end to the hook 63 carried at the free end of the composite spring 64.

Roller support.—The rollers 59, 60 and 10 61 are all supported on a framework, which comprises the beams 65 and 66, see Figs. 3 and 4. These beams are pivotally mounted at their outer extremities on the levers 67 and 68, see Figs. 4 and 11. The lever 67 is 15 connected with the rock shaft 69, while lever 68 rocks on shaft 70, which has a pivotal connection with the stationary framework.

Actuation of wire wheel supporting frame.—As above pointed out the cam 44, on 20 shaft 31 is in operative relationship with the regulating pulley 26. This cam 44 coöperates with the cam roller 45, against the tensions of springs 71, to actuate, through rock arm 72, the shaft 69, to rock the lever 67. 25 This results in the reciprocating movement of the beams 65 of the framework supporting the rollers 59, 60 and 61 and the wire wheel.

The formation and operation of the cam 30 44 is such, with respect to the other operating mechanisms of the machine, that the supporting mechanism of the wire wheel will have a reciprocating movement, said movement in one direction being in the direction of the movement of the clay bar 35 and at the same rate of speed, said movement with the clay bar beginning before the wire engages with the bar, and continuing until it shall have passed through the clay 40 bar, due to the rotating movement of the wire wheel. After the wire has passed through the clay bar, the wire wheel supporting means will be returned to initial position to repeat the operation. It is also 45 to be understood that the bottom slit plates 73 and 74, the side slit members 75 and 76, and associated mechanism are all supported by and move with the framework supporting the wire wheel.

50 It is to be noted that the three rollers 59, 60 and 61 are split rollers, one section or element provided with an adjusting screw 77, see Fig. 11 to maintain the required distance between the two sections to maintain 55 a perfect fit between the said roller elements and the peripheral channel 78 of the wire wheel 42; adjustment being made from time to time to take up wear. These rollers are for instance, feathered on the shaft 79 and 60 the set-screws 80 coöperate in maintaining their proper positions thereon.

Wire supporting mechanism.—The pin or stop member or stud 81 is secured to the ring 42 and is provided with shoulders 82

to engage the bifurcated end of spring 64 65 to limit its outward movement. The said pin 81 is maintained in position by the set-screw 83. The spring 84 is adapted to lie over the top of hook 63 to prevent the accidental disengagement of the wire therefrom. 70 The leaf spring structure 64 is maintained in position by the clamp bolt 85 including a member 86 having downwardly extending wings for keeping the shorter leaves of the spring structure in alinement; it being noted 75 that the bifurcated end of the longest member straddles the pin 81.

Side slit members support.—The construction of the supporting mechanism for side slit members 75 and 76 is shown in Figs. 12 80 and 13. The bar 105 is provided with the slot 106 through which is secured the bolt 107 for the adjustable engagement of said bar 105 with the framework supported by the beams 65 and 66. Upon this bar 105 85 is pivotally mounted at 108 the bracket 109 which carries slit member 75 or 76, as the case may be; that is to say, the supporting structure of each member is substantially the same. To a free end of bracket 109 is secured, at 110, one end of a slide rod 111, carrying the spring 112, for normally maintaining the said member 75 in the vertical position against a fixed stop 117 on member 105. By this construction it is provided 90 that when the wire encounters a stone or other obstacle in the bar, the members 75 and 76 will swing back to permit the escape 95 of the same beneath them.

Wire cleaner.—In connection with the 100 same supporting mechanism is provided a clamping device 113 of suitable formation, shown in Figs. 12 and 13, carrying the strip 114 of flexible material such as felt or rubber, projecting slightly into the path of 105 travel of the wire 43, for the purpose of wiping therefrom any substances which might otherwise stick to the wire. The plectrum 115 also extends across the path of travel of the wire, to vibrate the same, as 110 a further means for freeing it from substances that would otherwise cling thereto.

Regulating frame construction.—The regulating frame comprises the wooden beams 88 which are bolted to the angle irons 46. In 115 the beams 88 are inserted the arguto or improved wooden bearings for the rollers 89 supporting the regulating belt and to the beams 88 are also secured the brackets 90 forming a part of the ball-bearing support 120 of the frame as indicated in Figs. 19 and 20.

Adjustment of regulating belt.—The roller 91 supporting the other end of the regulating belt from that supported by the regulating pulley, is mounted on a frame 92 which 125 is slidably connected with the frame comprising the angle irons 46, and is provided with lugs 93 and 94, forming bearings for

the screw 95 which is threaded in the lug 96 which is connected with the frame comprising the angle irons 46, see Figs. 1 and 17. A hand wheel 97 is adapted to operate 5 the screw 95 through the beveled gear 98 to secure the proper tension of the belt.

Carrying-off belt and bifurcated slit plate.—As will be seen by an inspection of Fig. 3, the carrying-off belt 118 is narrower 10 than the regulating belt 25. As a matter of fact it is considerably narrower than the length of the bricks delivered thereto. It will be remembered that the slit plates 73 and 74 are reciprocated with the cutting 15 mechanism, and therefore plate 73 moves toward and away from belt 118. As the severed bricks are being pushed across said plate 73 it is important that they should not be caught between any undue space existing 20 between said plate and the carrying-off belt. For this reason the plate 73 is made with wings or extensions flanking the belt 118 so that as the bricks are pushed over this plate they are supported by the wings until they 25 are safely engaged by the belt 118. It will be noted that the top of plate 73 is approximately flush with the top of belt 118, and as the bricks are pushed along over plate 73 they are safely landed on belt 118 without 30 any shock or jar.

Operation.—It is to be noted that the wire engages the clay bar at an angle with the top plane and the exposed side of the bar as will be evident from an inspection of Fig. 2. 35 That is, the wire enters the top and left side of the bar always moving inwardly into the clay bar until it reaches the slit plates. This results in a smooth clean cut at the margin of the bar, without making 40 ragged edges, whereas if the wire left the bar moving outwardly through the surface, except where protected by the slit plates, a ragged or feathered edge would be left. The course of the wire through the bar also 45 assures the carrying of any hard obstruction such as a stone, safely over the bottom slit plates, and safely under the spring controlled side slit plates.

What I claim is:—

50 1. In combination with a brick machine, having means for moving a bar of clay, a cut-off wire and means for moving the same across the path of travel of the bar, bottom slit plates and side slit plates, the side slit 55 plates pivotally supported and spring controlled, having their lower ends adapted to swing in the direction of travel of the wire.

2. In combination with a brick machine, having means for moving a bar of clay, a 60 cut-off wire, means for moving the same through the bar, a reciprocating frame for moving the wire with the bar during the cutting operation, a carrying-off belt adjacent thereto, and a slit supporting plate on

the reciprocating frame having extensions 65 flanking said carrying-off belt.

3. In combination with a brick machine, having means for moving a bar of clay, a cut-off wire, means for moving the same through the bar, a reciprocating frame for 70 moving the wire with the bar during the cutting operation, a carrying-off belt adjacent thereto, and a slit plate having extensions projecting on both sides of the carrying-off belt and at substantially the same 75 level.

4. In combination with a brick machine, having means for moving a bar of clay, a cut-off wire for moving the same across the path of travel of the bar, a reciprocating 80 frame supporting and moving the wire with the bar during its cutting operation, a carrying-off belt, and a slit plate having wings or extensions flanking the belt as and for the purpose specified.

5. The combination with a wire wheel and a cutting wire carried thereby, of a spring carried by the wheel, a stud carried by the spring and engaged by one end of the wire, and a spring clip between the stud and the 90 spring.

6. The combination with a wire wheel and a cutting wire carried thereby, of a spring carried by the wheel, a stud carried by the spring and engaged by one end of the wire, 95 and a spring clip connected with the stud for normally maintaining the wire thereon.

7. The combination with a wire wheel and a diametrically disposed cutting wire carried thereby, of a leaf spring carried by the 100 wheel and operatively connected with the wire, said leaf spring having a recessed end, a stud, carried by the wheel, within said recess, means for clamping the leaf spring to the wheel and means connected with said 105 clamping means for maintaining the shorter leaves of the spring structure in alignment.

8. In a cut-off mechanism of the class described, the combination with the wire wheel of supporting and reciprocating means 110 therefor, comprising a rock shaft, a frame comprising a lever connected to the rock shaft, a pivoted lever, a plurality of beams movably connected with said levers, and a plurality of rollers carried by the frame and 115 operatively connected with the wire wheel.

9. In a cut-off mechanism of the class described, the combination with the wire wheel of supporting and reciprocating means therefor, comprising a rock shaft, a frame 120 comprising a lever connected to the rock shaft, a pivoted lever, a plurality of beams movably connected with said levers, cam controlled means operating relatively to the movement of the clay bar for moving the 125 rock shaft, and a plurality of rollers carried by the frame and operatively connected with the wire wheel.

10. In a cut-off mechanism of the class described, the combination of a longitudinally movable power shaft, a cutting wire and a movable regulating frame operatively connected therewith, a friction element connected with the power shaft and controlled by the movement of the regulating frame, a
- thrust box for the power shaft and a lever operating between the thrust box and the regulating frame.

HOWARD K. KING.
